EX

No. 15,114

July 1, 1884

UNITED STATES PATENT OFFICE.

PAUL GROEBER, OF NEW YORK, N. Y.

DESIGN FOR WALL-PAPER.

SPECIFICATION forming part of Design No. 15,114, dated July 1, 1884.

Application filed April 11, 1881. Term of patent 21 years.

To all whom it may concern:

Be it known that I, PAUL GROEBER, a citizen of the United States, residing in the city of New York, county and State of New York, have invented and produced a new and original Design for Wall or Ceiling Covering, which is especially intended as a wall-hanging.

The drawing represents a front plan view of the design.

10 The design is floral in its character, treated in the Japanese style.

The design represents three descriptions of flowers, *a b c*, in full bloom, surrounded with pinnatifid and serrated leaves *d e*. A seed-pod, *f*, is shown with three lobes, and a leaf-bud, *g*, about to expand. The stems *h* are treated as if of mature growth, having reached

the condition of woody fiber with knots and excoriations on their surfaces. The foliage and flowers are treated in a semi-conventional manner and the groundwork ornamented with a finely-granulated surface.

The design is continuous in all directions, and has an even appearance on the wall, which is agreeable to the eye, and harmonizes with all styles of furniture.

I claim—

The design for a wall or ceiling covering, consisting in the ornamentation shown in the accompanying print.

PAUL GROEBER.

Witnesses:

PHILLIPS ABBOTT,
JOHN MICHAEL.
